UNITED STATES PATENT OFFICE.

ALBERT C. A. HOLZAPFEL, OF LONDON, ENGLAND.

CONSTRUCTION OF VESSELS.

SPECIFICATION forming part of Letters Patent No. 476,643, dated June 7, 1892.

Application filed January 8, 1892. Serial No. 417,604. (No model.)

To all whom it may concern:

Be it known that I, ALBERT CHARLES AUGUSTUS HOLZAPFEL, a citizen of England, residing at 116 Fenchurch Street, in the county 5 of London, England, have invented new and useful Improvements in Ships and other Structures, of which the following is a specification.

My invention relates to the construction of 10 ships and other structures wherein plates flanged on all four sides are employed; and it has for its object to improve such constructions by a novel arrangement and combination of parts whereby great longitudinal and 15 transverse strength is provided.

To this end my invention consists in the novel construction, arrangement, and combination of parts hereinafter described and claimed, reference being made to the accompanying drawings, in which—

Figure 1 is a part outside elevation of a ship constructed of flanged plates according to my invention. Fig. 2 is a part inside view. Fig. 3 is a perspective inside view of some 25 of the plates. Fig. 4 is a perspective of one of the plates detached to a larger scale. Fig. 5 is the blank for the connecting-plates. Fig. 6 is a perspective view of the finished connecting-plate. Fig. 7 is a vertical section on 30 line X X, Fig. 2. Fig. 8 is a horizontal section on line Y Y, Fig. 2; and Fig. 9 is a bottom section with the transverse ties constructed so as to form closed cells for ballast.

In the drawings the letter A designates a 35 plate, which is provided with rearwardly-extending flanges on all four of its sides. These plates are placed end to end in layers one above the other. Heretofore it has been usual to dispose these plates in such a manner that 40 the butt-joints of the plates in the several layers are in the same vertical plane; but when so arranged there is a deficiency of longitudinal strength.

According to my invention I so arrange the 45 plates A that the butt-joints of those of one layer are not in the same vertical line with the butt-joints of the layer of plates next above or below. As shown in the drawings, the butt-joints of the plates of the first and 50 third layers are in line with each other and the butt-joints of the plates of the second and

fourth layers in line with each other, but out of line with the butt-joints of the first and third layers. I prefer this arrangement of the plates; but it is obvious that this arrangement of the plates may be varied without departing from the spirit of my invention. For example, the plates of the first and fourth layers may be so arranged that their butt-joints are in the same vertical line and the 60 butt-joints of the second and fifth layers are in a common vertical line, but out of line with the butt-joints of the first and fourth layers. By this novel arrangement of flanged plates greater longitudinal strength is provided than 65 in other structures in common use.

The novel arrangement of flanged plates described has a tendency to decrease the strength in a direction transversely of the plates, and in order to provide the requisite 70 strength in this direction I employ the following instrumentalities.

One end flange of each plate is made sufficiently deeper than the others for receiving a line of rivets, as shown at Figs. 3, 4, and 7, 75 for fixing a tie B thereto, and the plates of the several layers have their projecting transverse flanges a so arranged that those of the first, third, fifth, &c., layers are in line, and also that those of the second, fourth, sixth, 80 &c., are in line. At the middle of each plate is fixed a transverse connecting-plate C. This plate is formed of a blank having the configuration shown at Fig. 5, the middle portion b being of the same depth as the flanges a of 85 the plates A, while the two side wings b' are of the same depth as the other flanges of the plates. These wings are then bent to a right angle, as shown at Fig. 6, the length of the plate of the outside of such bent wings or 90 flanges being such as to fit between the longitudinal flanges of the plate, to which the flanges are then riveted, as shown more particularly in Figs. 3 and 8. These plates C are fixed in such positions within the plates A 95 that those fixed in the plates of the second, fourth, &c., layers have their projecting part b in line with the deep flanges a a of the plates of the first, third, &c., layers, while those fixed in the last-named plates are in line with 100 the flanges a a of the second, fourth, &c., layers of plates, so that the transverse angle-

iron or other ties B can be fixed not only to the flanges *a a* of the plates that have their butt-joints in line, but also to the plates of the intermediate layers by means of the connecting-plates C.

The transverse ties B can either be of angle, T, or other desired section and constitute an equivalent to the ribs of ships built in the ordinary manner. They may also be made of simple plates, as at Fig. 9, and may in that case serve to form closed ballast-cells by having shallow flanged plates D riveted to their upper ends, as shown.

What I claim is—

- 15 1. The combination, in a ship or other structure, of plates A, provided with interior flanges arranged in layers, one of said flanges *a* of said plates being deeper than the others, the flanges *a* of the plates of one layer being out of line with the flange *a* of the plates of other layers, and transverse ties B, connected to the said flanges *a*, substantially as described.
- 20 2. The combination, in a ship or other structure, of plates A, provided with interior flanges arranged in layers, one of the flanges *a* of said plates being deeper than the others, the flanges *a* of the plates of one layer being out of line with the flange *a* of the plates of other lay-

ers, connecting-plates C, secured to said plates A, and a transverse tie B, secured to the flanges *a* and connecting-plates C, substantially as described.

3. In a ship or other structure, the combination, with plates A, provided with flanges, one of said flanges *a* being deeper than the others, the flanges *a* of the plates of one layer being out of line with the flange *a* of the plates of other layers, of connecting-plates C, secured to the plates A in line with the flanges *a*, transverse ties B, secured to said flanges *a* and connecting-plates C, and flanged plates D, connecting the ties B to form closed ballast-cells, substantially as described.

In testimony whereof I have signed my name to this specification, in the presence of two subscribing witnesses, this 21st day of December, A. D. 1891.

ALBERT C. A. HOLZAPFEL.
